UNITED STATES PATENT OFFICE.

JAMES H. EGAN, OF OCEAN CITY, NEW JERSEY.

SLOT-MACHINE.

1,213,849.

Specification of Letters Patent. Patented Jan. 30, 1917.

Application filed July 18, 1916. Serial No. 109,940.

To all whom it may concern:

Be it known that I, JAMES H. EGAN, citizen of the United States, residing at Ocean City, in the county of Cape May and State 5 of New Jersey, have invented certain new and useful Improvements in Slot-Machines, of which the following is a specification.

This invention relates to so-called slot machines of that type employed to deliver an 10 article or articles upon the deposit of one or more coins of proper value, and it is particularly intended for delivering tokens or "checks" which may be used for the purchase of sodawater or other goods, the object 15 being to provide an improved device of the kind which may be operated by a purchaser to obtain soda checks or the like which can afterward be exchanged for the goods.

20 In the present machine the proper coin acts to form a connection between a pusher which is operated by hand and a delivery plate or plates which work under the bottom of a magazine containing the tokens to be 25 delivered. There are two of the delivery plates and magazines, and the arrangement is such that one or both can be operated.

The invention is illustrated in the accompanying drawings in which—
30 Figure 1 is a vertical section on the line 1—1 of Fig. 2. Fig. 2 is a central vertical section across the machine. Fig. 3 is a top plan view of the base of the machine with the magazines and upper part removed.
35 Fig. 4 is a top plan of the machine. Fig. 5 is a plan view of the base with the delivery plates and pushers shown in Fig. 3 removed. Fig. 6 is an inverted plan view of the bottom of the upper part of the machine 40 which was removed in Fig. 3. Fig. 7 is a detail of the operating lever.

Referring specifically to the drawings, 6 is a hollow base of inverted cup-shape having openings 7 to permit the fall of a token 45 into a delivery chute 8, and also having slots 9 to permit the passage of coins into the runways 10 leading to exposure runways 11 which extend outside of the base and which deliver into a cash box 12 in the bottom 50 thereof. Upon this base is mounted a glass container 13 in which are cylindrical magazines 14 which may be filled with tokens or "checks" through slots 15 in the top thereof. Behind the magazines the container has a 55 compartment 16 closed by a bottom 17 for holding straws 18 or the like. The container top 19 also has openings 20 communicat-

cating with coin chutes 21 which correspond with the magazines. The bottom plate 17 of the container has on the under side there- 60 of depending frames 23 which support horizontal plates 24 each of which has an opening 25 through the same. The front end of each of these openings is reduced as indicated at 26, to a width slightly less than that 65 of a proper coin delivered thereto from the chute 21, while the wider part of the opening is sufficiently large to allow the coin to drop when it is moved to the rear.

The container is connected to the base by 70 a pair of rods 28 extending through lugs 29 on the inside of the base.

The top plate 30 of the base has a central rib 31 at each side of which is a groove 32, and mounted to slide upon this plate, at 75 each side of the rib, is a delivery plate 33 which has a flange 34 that travels in the groove 32, which serves to guide and retain the plate. Each plate also has an opening 35 which normally registers with the bottom 80 of the corresponding magazine 14, so that the lowest token rests in the opening in the delivery plate, where it is normally supported by the adjacent part of the top plate 30 and by a small tongue 36 on the under- 85 side of the plate. Each delivery plate also has a coin slot 37 located behind the opening 30; also a guide slot 38 in which works a pin 39 projecting from the plate 30.

Mounted upon or above the delivery plates 90 is a sliding cross-shaped plate 40, which I will term the pusher plate. This is guided by a pin 41 which projects through a slot 42 therein and another pin 43 which projects through a slot 44 therein, these pins or screws being 95 set into holes 45 in the rib 31. The rear end of the plate 40 is turned up as indicated at 46 and a spring 47 is connected thereto, and to the pin 41, and tends to hold the pusher plate in forward position. This 100 plate has two arms 48, and mounted upon each arm is a short chute section, comprising opposite front and rear plates 49, and this section is in line with a slot 50 in the plate. Pins 51 act to stop the forward 105 movement of the pusher plate, due to the spring, and this chute section 49 projects upwardly through the space 25 between its edges 26 and 27 and between the side pieces 23 of the frame above described, when the 110 parts are assembled.

60 is a chute for undersized coins, adapted to return the same to the outside of the machine.

Each delivery plate has at its outer edge a depending arm 61, with a rearwardly projecting finger 62 which, when the delivery plate is pushed back, passes through an opening 63 in the chute 10 and acts to stop a coin in said chute. Each plate also has a depending arm 64 with a forwardly projecting finger 65 which, when the delivery plate is advanced, acts to stop a coin in the exposure chute 11 and expose the same at the opening 66 therein.

For operating the pusher plate I provide a finger lever 70 which is pivoted at 71 to a bracket 72 in the container, and this lever 15 has a projection 73 which extends into an opening 74 in the front end of the pusher plate.

The operation is as follows: The magazines being loaded with tokens or "checks", 20 the lowermost rest in the openings 35 of the respective delivery plates 33, where they are supported by the adjacent parts of the top plate 30 and the tongues 36. When the proper coin is deposited in one of the coin 25 chutes 21 it falls through the same and between the two plates 49, where it is stopped by the edges 26 of the plate 24, in such position that the lower edge of the coin will extend or project into the slot 37 in the delivery plate 33. This connects the delivery plate with the pusher plate, at that side of the machine. Then by pressing on the lever 70 the pusher plate 40 is pushed back and carries with it the delivery plate 30 on that 30 side, and this delivery plate carries backward the token in the opening 35 until it registers with the opening 7, when the token will fall through the opening and out the delivery chute 8. At the same time, at 35 the limit of the backward movement, the coin reaches the wide part 27 of the stop plate 24, and registers with the slot 9, and will then be released and will drop through said slot into the chute 10 where it is temporarily held by the finger 62. When the 40 finger lever 70 is released the pusher and delivery plates are returned by the spring 47 to original position and the finger 62 is then retracted and the coin in the chute 10 rolls 45 out into the chute 11 where it is stopped and held and can be seen through the opening 66. At the next operation, the coin in the chute 11 is released by the backward movement of the finger 65 and drops from said 50 chute into the cash box 12.

If two coins are deposited in the chutes 21, both of the delivery plates 33 will be connected to the pusher plate 40, and when the latter is pushed back both of the delivery plates will also be pushed back, and will deliver two tokens, one from the five cent

magazine and one from the ten cent magazine, for example.

If an undersized coin is deposited in the chute 21 it will pass between the edges 26 65 of the stop plate 24 and fall down through the opening 37 into the chute 60 by which it will be returned outside of the machine.

It will be seen that by means of the double arrangement either one or two tokens may 70 be delivered at a single operation. Thus if a five cent drink is wanted a five cent token may be obtained. If a ten cent, or two five cent drinks are wanted, the ten cent side is 75 operated; or both a ten cent and five cent token may be obtained simultaneously by operating both sides. The exposure chutes 11 enable the deposited coins to be seen after they pass through the operating mechanism, and before they are dropped into the cash 80 box.

I claim:

1. The combination of a magazine for articles, a sliding delivery plate thereunder having an opening for the bottom article, 85 and a coin slot, a coin chute, a frame at the lower end of the coin chute having a narrow part adapted to engage and stop a coin with its edge in said slot and a wider part adapted to release said coin, a pusher plate 90 slideable upon the delivery plate and having a short chute section projecting into said frame and adapted to engage a coin stopped therein and shift the same to the wider part of the frame.

2. The combination with a sliding delivery plate, of an operating coin mechanism associated therewith, an exposure chute leading from said mechanism, having an opening through which a coin may be seen, and an arm carried by said plate and projecting across said chute in position to stop a coin opposite said opening at each operation of the plate.

3. The combination of a coin chute having a frame at the lower end thereof provided with an opening having a narrow end adapted to stop a coin, and a wide end adapted to release the same, a sliding article delivery plate having a slot into which the edge of a coin projects when it is so stopped, and a sliding pusher plate having a short chute section located between said chute and slot and projecting into said frame and adapted to engage a coin therein and shift the same to the wide end thereof to release the same, said coin acting to slide the delivery plate when so shifted, and means to restore the plates to original position.

In testimony whereof I affix my signature.
JAMES H. EGAN.
